(57) **CLAIM**

I claim the ornamental design for a jewelry chest, as shown and described.

DESCRIPTION

FIG. 1 is a perspective view of the jewelry chest showing the new design;

FIG. 2 is a second perspective view thereof with the top and some drawers shown in the open position;

FIG. 3 is a front elevational view thereof;

FIG. 4 is a top plan view thereof;

FIG. 5 is a rear elevational view thereof;

FIG. 6 is a bottom plan view thereof; and,

FIG. 7 is a right side elevational view thereof, the left side elevational view being a mirror image thereof.

The dotted lines are for illustrative purposes only and form no part of the claimed design.
